TUBE SECTIONING MACHINE

Marshall E. Gazette, Roslindale, Mass., assignor
to Hercules Container Corp., Boston, Mass., a
corporation of Massachusetts

Application August 19, 1947, Serial No. 769,375

4 Claims. (Cl. 164—69)

1

This invention relates to tube sectioning machines.

More particularly, it provides a machine which selects single paper tubes in succession from a hopper, divides each into sections of predetermined lengths, and deposits the sections in separate bins. The machine is herein illustratively described with reference to paper tubes because such are likely to be its principal field of utility, but the tubes may be of other material. Paper tubes are used industrially in a wide variety of circumstances, which in addition to uses strictly as tubes include containers for foods, cosmetics and other commercial articles, and covers for such, as well as for wrappers, rollers, etc. Such tubes are manufactured by well known processes of continuous operation, for example, by winding a pair of strips of paper around helically so each strip overlaps the edges of the other. For convenient handling these are cut into uniform length, herein called stock length, which, in the present example, is illustratively assumed to be 20 inches. Such tubes constitute the raw material which the machine of the invention will cut into sections, assumed to be wanted in six-inch lengths, each to become the body of a cylindrical paper box. The machine, therefore represented set up for a particular diameter of tube and length of section, can be set up to operate similarly to produce other lengths and to work on other sizes of tube. In this set-up the machine is to cut each 20-inch stock tube into three six-inch sections, and to trim off the residual margin at each end.

The machine is wholly automatic, in the sense that the duties of the operator consist in occasionally depositing an armful of stock tubes in the hopper, and in occasionally substituting an empty bin for one that has become filled with sections cut by the machine.

Objects of the invention are to improve efficiency as compared with machines heretofore known, by eliminating the possibility of blockages to which other machines are subject; increasing the speed of output, and so to reduce the cost of the product; reducing the floor space requisite for the operation of a machine of this sort; and operating the mechanism by air power in a cycle which includes the holding over of a charge of motive power air, at partial pressure, thereby reducing the need and cost of power for the succeeding cycle, and incidentally permitting operation by a less costly air compressor.

Details of mechanisms embodies and combined in the machine for the accomplishing of these

2

objects will appear as the description proceeds, and are shown in the accompanying drawing.

It will be understood that the description and drawing disclose only an example, and that many variations may be made.

In the drawing, which is somewhat diagrammatic, with parts omitted for clearness:

Figure 1 is a left end elevation of the machine which is being described;

Figure 2 is a front elevation of the same;

Figure 3 is a left end elevation of the same, in section on the line 3—3 of Figure 2; but at a different stage of operation;

Figure 4 is a plan of the same;

Figure 5 is a plan of parts of the same, in section on the line 5—5 of Figure 3, enlarged;

Figure 6 is a plan, in section as on line 6—6 of Figure 3, enlarged, showing the gang of cutters; but showing the mandrel inserted; and

Figure 7 is a detail of one of the gang of cutters operating on a tube, greatly enlarged.

The general structure and operation are that a selector drum 10 takes tubes T singly from a hopper at the top, and drops each in turn into a V-shaped cradle C made of rods 12 in which gravity moves it to the vertex position T—40, where it will receive a mandrel 14 that will be shot endwise into it by a sort of air gun that is fixedly aimed, comprising a crosshead 15 joining a pair of pistons 16 that are air-puff-driven out from long parallel cylinders 17. The leading end of the mandrel emerges from the tube into a rotating cup clutch 18 (Figures 2, 6) which sets the mandrel and tube into rotation. At the same time a gang of rotating cutters 20 (Figures 3, 2) becomes swung against the side of the tube; cuts it into the predetermined sections; and swings away. Thereupon other pistons 61 (Figure 4) in reversely pointed cylinders 71 shoot the mandrel out of the tube and as the mandrel recedes the sections of tube fall separately from the places seen in Figure 2 where they were when being cut. The pistons travel in their cylinders without close packing, and thus the air pressure applied becomes so quickly reduced that a succeeding oppositely directed air puff is effective to move the mandrel reversely. The interval of time between successive similar strokes is so short that the high air pressure used in a stroke is not wholly lost. It is not wholly exhausted but becomes reduced enough to let the opposing stroke be effective.

The machine includes pipes and valves and operating cams, for compressed air supply for the linear drives; power transmission and control de-

vices for the various rotatory drives; and means to synchronize the various actions in repetitive cycles.

In the drawing, elements which belong distinctively to the supporting frame are marked F, and tubes on which the machine operates are marked T. Owing to the long and straight nature of tubes, the hopper is a skeleton affair made of a pair of separated parallel inclined bars 30 (Figures 3, 4) which slope toward other bars 31 to form a sort of V into which a supply of stock tubes T can be thrown and will be held in horizontal parallelism. A transverse upright plate 33 constitutes an alignment wall at the left end of the hopper. The front bars 30 do not fully close the lower part of the V; and the space thus left is closed by a rotating drum selector 10. This is skeletonized, consisting only of its rotating shaft 9 and two disks 10, one at each end of the drum, the disks having edge-notches 34, aligned in pairs together lengthwise of the drum, into which any of the tubes in the hopper can settle and be carried around with the drum. As shown, these notches are semi-circular, conforming in size to the diameter of tubes which are to be handled, to encase loosely about half of the cylindrical surface of any single tube T. The inward face of each disk has a shoulder 10' of reduced diameter with larger notches 35, which conform to about a quadrant of a cylindrical rolling tumbler 11 which is a rather large hollow shell tethered loosely in the hopper, parallel to the tubes T, by straps 37 whose ends have anti-friction rollers 38 hooked into the open ends of this tumbler. The tumbler is made with diameter so great that it will rise and roll over any tube T which is being carried past it in a notch 34. Ordinarily this rising and falling is sufficient to agitate the mass of tubes so that every successive notch 34 will acquire a tube as it passes the lower part of the hopper; but occasionally some disarray of the tubes will make one or more notches 34 pass empty. In the absence of a tube to raise it, the tumbler will settle into its own deeper notch 35, portrayed in Figure 3, and its movement into and out of these notches coupled with its rotational frictional drag on tubes, and gravity, will agitate the mass to restore horizontal parallelism of the tubes T so that the notches 34 will again pick them up.

A curved strip 39 of spring metal extends beside the course of the selector drum to confine each tube in its notch 34, and ends underneath the drum to let the tube fall into the V-cradle, marked with a C and made of bars 12, which receives and by gravity places and holds each successive tube in the vertex position marked T-40 in line to receive axially the mandrel 14. For tubes of other diameter the cradle bars can be adjusted to produce proper alignment of the tube's axis with the axis of the mandrel.

The mandrel 14 is slideable lengthwise through a bearing 42 on the frame F and is rotatable therein, and is also rotatable in its bearings 43 on the crosshead 15 which drives it. The crosshead has carriage wheels 44 that run on horizontal side rails 46 of the frame F. Mandrels of differing diameter can be substituted, with the mandrel's axis always at the same elevation level, by using mandrel bushings of suitably differing sizes in the crosshead bearings. The propulsion of the crosshead for shooting the mandrel in the tube is by a pair of parallel pistons 16 which travel in cylinders 17, one on each side of the centrally mounted mandrel, driven by compressed air which enters these cylinders 17 at

the right (Figures 2, 4) through vertical pipe 48. This is fed from the main air supply 51 at the left of the machine through the long pipe 49 (Figures 2, 3 and 5) controlled at self-closing valve 47 (Figures 3, 5) by a cam 50 which is adjustable on the shaft 52 for setting its time and dwell to deliver a puff of air at each revolution of the cam. For propulsion of the mandrel 14 in withdrawal direction a pair of pistons 61 beside the mandrel run in the cylinders 71 which receive puffs of compressed air through vertical pipe 58 (Figure 1) fed by pipe 59 from the main air supply 51 through self-closing valve 57, controlled by cam 60 which is similar to cam 50. 10 These two cams are on the same shaft 52 and operate at different times; but for clearly showing the relation of the cam 60 to the valve 57 this cam 60 is represented about to open that valve and so is not in the part of its circuit which it occupies when the valve cam 50 is in its position shown in Figure 3, about to operate its valve 47.

The main shaft 8 receives its power from any suitable source, as by belt 81, for which Figure 1 indicates an electric motor 80 assumed to have a reducing gear. From the main shaft 8 a V belt 82 drives a first countershaft 86. This is a short shaft at mid-height of the machine, wholly at the left of the section line 3-3 in Figure 2. It is aligned with the mandrel 14, and, the end of this shaft which is toward the mandrel, immediately at the left of said section line, carries a contact collet clutch 18 into which the leading end of the mandrel strikes, after passing completely through the tube that is in position T-40.

From this countershaft 86 a belt 88 drives a second countershaft 90 from which another belt 92 drives a third countershaft 94 which carries a gang of cutters 20. The cutters may be spaced apart along this shaft according to the desired lengths of sections of tube. This shaft has bearings on a swinging frame 96 (Figures 3 and 6), approximately horizontal, which is pivoted at 100, seen in Figure 6 and indicated as a dot and circle in Figure 3. This frame is a lever whose power end is at the top of an upright thrust-rod 102, the foot of which stands pivotally on an approximately horizontal lever 104 that is continuously pulled upward by a spring 106 to press its terminal roller 108 upward against a cam 27.

45 The high radius dwell of this cam depresses the roller and lever 104, thus lifting the cutter shaft 94 and cutters 20 into the tube position T-40. This cutter-controlling cam 27 is loose on its shaft 29, which is chain driven, as indicated by the dotted line 114, from the main shaft 8; but is connectible to its shaft 29 by a single-revolution clutch 116, the tripping of which is effected by a lever and strap 118. This clutch-tripping lever is fulcrumed on the frame F at 120, Figure 3; and its power end has an upward slant, Figure 2, in position to be struck and depressed by the leading edge of the crosshead 15 as the mandrel reaches the end of its stroke into the clutch 18 that starts the tube rotating.

60 46 This clutch 116 is of the type which is effective as a clutch only when tripped; and releases at the conclusion of a single revolution, until it is tripped again. It leaves the cam 27 and the cutters 20 inactive until the lever 118 is again depressed. However the cutters 20 rotate continuously at speed. The swing of the cutter shaft 94 toward and from cutting position is approximately perpendicular to its driving belt 92, and is very short, therefore imposes no undue stretch on its driving belt.

Chain 122 from the main shaft 8 driving the valve cam shaft 52 and the speed-reducing chain drive from that to the selector shaft 9 indicated by dotted lines in Figure 1 and the chain drive 114 from the main shaft to the cutter-control cam shaft 29 maintain synchronism in the action of these elements so that the depositing of a tube at the position T-40°, the supporting and rotating of it by a mandrel, the cutting of it into sections and the delivery of these sections accompanying a withdrawal of the mandrel constitute a complete cycle followed immediately by the depositing of another tube as the beginning of another cycle.

Means is provided to adjust the air power with which the mandrel is impelled, and to cushion the impact at each end of the stroke. The air supplied to the machine may be as is convenient, e. g. from storage at 200 pounds; but a reducing valve 53 brings the pressure down to whatever is desired for the particular work in hand, e. g. 60 pounds at each valve 47 and 51, admitted during a period which can be adjusted by changing the dwell of the cam 50 or 60. To soften the impact at end of stroke a rod continuation 64 of the mandrel is installed at the right in Figure 4, connected to the mandrel by coupling 66, having a bearing 65, in which the end part of the mandrel 14 is rotatable. This rod passes through a dash pot, indicated at 67, and in each direction from the dash pot carrying an adjustable collar 68 which can be set to engage the dash pot at the proper point for easing the terminal impact.

In operation the selector 10 rotates continuously at a rate which drops one tube T into the cradle C at each complete revolution of the shaft 52 which carries the cams 50, 60. In this cycle, gravity settles the dropped tube to the target position T-40°; the cam 50 opens valve 47 admitting to pipes 49, 48 and cylinders 17 a puff of air under pressure sufficient to shoot the pistons 16, crosshead 15, and mandrel 14 in guided flight through the tube, until the mandrel strikes the rotating target clutch 18. Immediately preceding, the crosshead 15 strikes and trips the lever 118 that actuates the clutch 116, so that it grips the shaft 29 and begins to rotate the cam 27 with it. But this cam stops when the clutch 116 stops at the end of one complete revolution. During that revolution the cam 27 pulls down the rod 102 and so swings the lever 96 that carries up the gang of cutters 20 into the position T-40° occupied by the mandrel 14 which by this time is both supporting and rotating the tube T. The cutters penetrate the tube as seen in Figure 7, dividing it into sections according to their spacing apart along their shaft 94. As the single revolution approaches its end, the cam 27 lets the spring 106 draw up the rod 102 to draw the cutter shaft 94 and the cutters 20 away from tube. Immediately thereafter the valve cam 60 reaches its position illustrated in Figure 1, and opens valve 57, to admit compressed air to pipes 59 and 58 to the cylinders 71 and pistons 61 to shoot the mandrel back out of the now sectioned tube. Before this the opposing pressure in cylinders 17 will have fallen enough for the pressure freshly admitted to cylinder 71 to do its work. An obstructing bushing 19, or sleeve prevents the tube from following the mandrel. Therefore as the mandrel moves each section falls from the place where it was being cut, and if the sections differ in length each can be received in a bin (not shown) allocated to its particular length. The valve cam

may be set for the valve 47 to open in the next cycle without delay after the positioning of the next tube, which should immediately follow the out movement of the mandrel, in order to salvage whatever pressure of air has not escaped from the cylinders 17. These cylinders and pistons 16 are designed to operate with very little packing of the piston in the cylinder, or none at all, in order that each puff shall quickly become dissipated in order to provide for effective action of the reverse puff. The inserting of the mandrel by powerful short blasts of air, herein called puffs and the consequent free flight of the mandrel as a missile to its target, has important useful effects, especially in comparison with any system in which the mandrel stroke is positively driven, as by gearing. One is that if the stock tube happens to be defective, or bent, so that the mandrel becomes jammed the freedom of the mandrel from positive drive safeguards the machine. Another is the speed which can be attained, both speed as a missile, and quick reversal, for high frequency of cycles. Since each piston acts only in one direction, and has no stuffing box, the propulsive high air pressure behind it diminishes quickly after the cut off of air supply, and is not fully restored by return of the piston. However the quickness of reversal catches some air at a pressure that is helpful in the succeeding similar stroke. By embodying two pistons in each direction one of the cylinder-piston combinations can over lie the other with great saving of space. The impositive character of the cutter control is also a safeguard, for this will not swing the cutters to working position if their control lever is not tripped by the air-driven mandrel reaching the end of its normal flight. The mandrel will be small enough to pass loosely through the tube which is at position T-40°. Its leading end should be slightly tapered, to make sure of entering the tube. The cradle C is preferably set, by adjustment of the bars 12, so that the inserted mandrel will contact the inner surface of the tube. The rotation of the mandrel, which begins when its impact seats the spring collet 18 against its fixed sleeve, will then rotate the tube by frictional drag. By coordinating the driving speed of the rotary system, which fixes the time between reciprocating puffs, and by adjusting the reducing valves 53 and the lengths of dwell of cams 50 and 60 for controlling the power of those puffs, in relation to whatever rate of piston's leakage is found to characterize any particular machine, the coordination can be attained in which a high rate of output of sectioned tubes is coupled with a substantial salvaging of the power used in one cycle for repeated use in the next cycle. The pipes 48 and 49 being rather long have their diminishing pressure boosted by the beginning of the next succeeding cycle. The time allotted for the cutting need be only long enough for the clutch and cam 27 to make their single revolution. The time for that is made precise in relation to the valve timing and selector timing by the interconnections of these parts by chain and sprocket drives, so that in close succession of events the machine sets a tube in target position, shoots the mandrel into it, cuts the tube into sections, and drops the sections by shooting back the mandrel.

I claim as my invention:

1. In a tube-sectioning machine of the type wherein there is a tube hopper, means for removing tubes singly therefrom to mandrel-receiving position, a mandrel, means reciprocating

ing said mandrel into and from successive tubes, tube cutting means, and means for stripping the cut sections from the mandrel; in combination, a V-cradle to which said removing means delivers each tube, and wherein gravity positions each tube at the vertex, this being a mandrel-receiving position, mandrel rotating means including a rotary open ended clutch having a spring collet seated against a sleeve fixed therein, this collet being aligned as a target behind said mandrel-receiving position at the vertex and clutching the leading end of the mandrel; said mandrel being connected to a wheeled supporting carriage, and parallel tracks on which the carriage is supported and along which the carriage is thrust by said reciprocating means for imparting swift motion to the mandrel on a course leading it through the tube at the mandrel-receiving position.

2. In a tube-sectioning machine of the type wherein there is a tube hopper, means for removing tubes singly therefrom to mandrel-receiving position, a mandrel, means reciprocating said mandrel into and from successive tubes, tube cutting means, and means for stripping the cut sections from the mandrel; in combination, a V-cradle to which said removing means delivers each tube, and wherein gravity positions each tube at the vertex, this being a mandrel-receiving position, mandrel rotating means including a rotary-open ended clutch having a spring collect seated against a sleeve fixed therein, this collect being aligned as a target behind said mandrel-receiving position at the vertex and clutching the leading end of the mandrel; a rotary shaft for said tube cutting means, supporting means therefor movable transversely to and from said mandrel-receiving position, a spring to draw said cutter shaft out of said supporting means, a second shaft, a cam on said second shaft for moving the first shaft to mandrel-receiving position, a one-revolution clutch on the second shaft for controlling the revolution of said cam, and a lever whose power end is located in the path of a part reciprocating with said mandrel and whose work end trips the one-revolution clutch to rotate said cam.

3. A tube-sectioning machine, having in combination a tube hopper, having in a lower part of its wall a rotating drum with notches for receiving and removing tubes singly; a relatively larger cylindrical tumbling agitator within the hopper for riding over tubes that are in those notches, a drum having deeper notches to receive and eject this agitator; a V-cradle to which the said drum delivers each tube, pointed downward to hold that tube in a mandrel-receiving position as a target; a mandrel; pistons connected to the mandrel and cylinders in which the pistons act, fixedly aimed at the target; and there being pipes, valves, and valve control means for supplying puffs of compressed air, to the pis-

tons; said cylinder-and-piston combinations being in mutually opposing pairs for reciprocating the mandrel toward and from said target; and each said piston being single acting, having leakage for dissipating its puff pressure during its stroke; the said pistons which act in one direction being located in overlapping relation to those acting in the opposite direction; a rotating clutch, open ended behind said target to receive, grip and rotate the leading end of the mandrel, whereby the target tube is rotated; a shaft with cutters thereon swing-mounted beside the target for swinging the cutters transversely toward the target; a single revolution clutch, with cam for swinging said cutter shaft; a lever for tripping this clutch, the power end of this lever being located to be engaged when the mandrel reaches the first said clutch, by a part which moves with the mandrel thereby to trip the single revolution clutch; and driving means, the said tube remover, valves controls, and single revolution cutter clutch being synchronized for cycles, each cycle comprising the said delivering of a tube to the target position, shooting the mandrel into that tube and the rotary clutch, swinging the cutters into and out from the target tube and shooting the mandrel back therefrom; there being an obstacle outside of the target position and close to the mandrel, preventing the sectioned tube from following the mandrel back; whereby the tube-sections are thus stripped from the mandrel and fall from the cradle.

4. A tube-sectioning machine, of the type having in combination a tube hopper, means for removing tubes singly therefrom to mandrel-receiving position, a mandrel and means to reciprocate it into and from successive tubes, mandrel rotating and tube cutting means, and means for stripping the cut sections from the mandrel; characterized in that the said removing means is a rotating drum constituting a lower part of the wall of the hopper, having peripheral tube-receiving notches; combined with a relatively large, freely rotatable, cylindrical tumbler within the hopper for riding over tubes that are in those said notches; said drum also having peripheral notches to receive and eject the tumbler for agitating and settling other tubes in the hopper.
